[57] CLAIM

The ornamental design for a table for portable cutting tools, as shown.

DESCRIPTION

FIG. 1 is a top plan view of a table for portable cutting tools, showing our new design;

FIG. 2 is a front elevational view thereof;

FIG. 3 is a rear elevational view thereof;

FIG. 4 is a somewhat enlarged right-end elevational view thereof; and

FIG. 5 is a somewhat enlarged left-end elevational view thereof.
